(57) CLAIM

The ornamental design for a sectional sofa with table, as shown and described.

DESCRIPTION

FIG. 1 is a perspective view of a sectional sofa with table, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of one of the two identical corner seat components of the sectional sofa with table of FIG. 1, shown separately to reveal aspects of the design that may not be apparent in other views;

FIG. 9 is a perspective view of one of the four identical armless seat components of the sectional sofa with table of FIG. 1, shown separately to reveal aspects of the design that may not be apparent in other views;

FIG. 10 is a perspective view of the table component of the sectional sofa with table of FIG. 1, shown separately to reveal aspects of the design that may not be apparent in other views;

FIG. 11 is a perspective view of the sectional sofa with table of FIG. 1, in a second alternate configuration;

FIG. 12 is a perspective view in a third alternate configuration;

FIG. 13 is a perspective view in a fourth alternate configuration;

FIG. 14 is a perspective view in a fifth alternate configuration;

FIG. 15 is a perspective view in a sixth alternate configuration;

FIG. 16 is a perspective view in a seventh alternate configuration;

FIG. 17 is a perspective view in an eighth alternate configuration;

FIG. 18 is a perspective view in a ninth alternate configuration;

FIG. 19 is a perspective view in a tenth alternate configuration;
 FIG. 20 is a perspective view in an eleventh alternate configuration;
 FIG. 21 is a perspective view in a twelfth alternate configuration;
 FIG. 22 is a perspective view in a thirteenth alternate configuration;
 FIG. 23 is a perspective view in a fourteenth alternate configuration; and,
 FIG. 24 is a perspective view in a fifteenth alternate configuration.
